UNITED STATES PATENT OFFICE.

ARTHUR H. STOKES, OF DETROIT, MICHIGAN:

FORM FOR FRONT AND REAR OF AUTOMOBILE-TOPS.

1,144,874.

Specification of Letters Patent. Patented June 29, 1915.

Application filed June 1, 1914. Serial No. 842,057.

To all whom it may concern:

Be it known that I, ARTHUR H. STOKES, a citizen of the United States, and a resident of Detroit, in the county of Wayne and State of Michigan, have invented new and Improved Forms for Front and Rear of Automobile-Tops, of which the following is a full, clear, and exact description.

This invention relates to improvements in devices for shaping or rounding the front and rear portions of automobile or other vehicle tops and more particularly to forms for such purpose.

The essential object of the invention is evolved by the provision of shaping devices of the class described constructed of suitable sheet material such as very thin metal, shaped to the required design to cause the front and rear portions of a vehicle top to take a rounding shape whereby a very desirable style and appearance is produced, as well as providing means permitting reinforcement of the cover or hood of the top at these particular points.

With the above and other objects in view, the invention resides in the peculiar combination and arrangement of parts to be hereinafter more fully described, illustrated and claimed, it being also an object to provide a device which is simple in construction, durable and efficient.

Reference is to be had to the accompanying drawings forming a part of this specification, in which similar characters of reference indicate corresponding parts in all the views, and in which—

Figure 1 is a side elevation of a vehicle top equipped with the improvement; Fig. 2 is a plan view of a fragmentary portion of a form constructed in accordance with the invention; Fig. 3 is a cross sectional view taken on the line 3—3 of Fig. 2 concluding with the complete device as shown in Fig. 2; Fig. 4 is a detail view of a modified form of the device.

In illustrating the application of the forms for front and rear of automobile or other vehicle tops, the body portion 10 of a vehicle is shown having a folding top 11 preferably constructed in accordance with the description set up in my co-pending application Serial No. 847,649, filed June 27, 1914. Ordinarily the front and rear portions of the cover or hood 12 when bent around the bows 13 and 14 form abrupt ends not desired in vehicle tops and which often

result in the destruction and wearing of the cover or hood at these particular points due to the constant strain thereon and especially when the top is folded. To obviate these difficulties I provide the forming or shaping member 15 at the front of the top and the forming or shaping member 16 at the rear of the top. These devices or members are preferably constructed of some sheet material such as thin sheet metal sufficient to sustain the strain and weight placed thereon without materially adding to the weight of the top, and as shown, the device 15 is of quadrantal cross section or substantially that of a quarter segment of a circle with a convex face portion 17 causing the cover or hood to be rounded. The device is fastened to the bow 14, as shown at 18, and may be constructed of a single section pressed or molded into shape or of an intermediate section 19 and end section 20 joined thereto by brazing, welding or otherwise, as shown in Fig. 4 of the drawings.

The forming or shaping device at the rear of the top is of larger curvature and like the rounded end portions provided for the form 15 is provided with rounded end portions 21 and straight portions 22 extending from its curved corner portion 23 forward and rearwardly respectively. In order to attach this form to the bow 13 it is provided intermediate or between its longitudinal edges with a plurality of alternately arranged longitudinal slots 24 and apertures 25, at either side of the latter of which similar apertures 26 are also provided. The bow is disposed beneath said slots and apertures or the form arranged to bring the parts in this relation with the ends of the bows conforming to the ends of the form or shaping device and with braces 27 secured to the inner face of the form at spaced distances through the apertures 26. After the application of the form to the bow the braces 27 will contact with the inner face of the bow at the arch thereof and are secured in position as by means of fastening devices or rivets 28 passing through the apertures 25, the bow and corresponding apertures in the braces.

The braces are mainly of angular form but between their extremities and the intermediate portion are bowed or made convexly arcuate inward to give the desired bracing effect and when the cover or hood 12 is secured over the frame of the top with its fas-

tening means passing through the slots 24 at the proper intervals allowed by the provision of these slots, the front and rear portions will be rounded and supported, as is 5 more particularly shown in Fig. 1 of the drawings. When the top is folded, the forms accommodate or produce housings for the bows. This is preferable as it makes the top fold up more neatly and completely, 10 thus reducing the bulky appearance of the top when folded. In this manner the rounded form piece on the rear bow serves as a mold for the slip-cover of the top when folded, thus enhancing the appearance of 15 the car and giving a curved appearance to the lower part of the folded top to accord with the lower part of the body at the back of the car.

Having thus described my invention, what 20 I claim as new and desire to secure by Letters Patent is:—

1. The combination with a vehicle top 25 provided with bows; of a convexly arcuate shaping device extended transversely across said top at one end thereof and having end members arranged longitudinally of said top, and means for securing the device to the respective bow.

2. The combination with a vehicle top 30 provided with bows; of a convexly arcuate shaping device extended transversely across said top at one end thereof and having end members arranged longitudinally of said top, the connection of the end members being rounded to shape a cover, and means 35

for securing said device and cover to the respective bow.

3. In a form for automobile tops, the combination with a bow; of a sheet metal device shaped in convex form and bent lengthwise 40 to fit the curvature of the bow and having a plurality of openings arranged longitudinally therein, and means for securing the device to said bow through said openings.

4. The combination with the bows of a 45 vehicle top; of a former to cause the cover of the top to take a rounding effect, said former comprising a sheet metal member convexly bent with rounded ends and having a plurality of openings longitudinally 50 thereof, braces connecting the former to a bow and a cover attached to the bow through the openings.

5. The combination with the bows of a 55 vehicle top; of a former to cause the cover of the top to take a rounding effect, said former comprising a sheet metal member convexly bent with rounded ends and having a plurality of longitudinal slots and intermediate openings, braces connecting the 60 former to a bow, and a cover attached to the bow through the slots.

In testimony whereof I have signed my name to this specification in the presence of two subscribing witnesses.

ARTHUR H. STOKES.
